UNITED STATES PATENT OFFICE.

BRADFORD H. WHITING, OF CHICAGO, ILLINOIS, ASSIGNOR TO WHITING CORPORATION, OF HARVEY, ILLINOIS, A CORPORATION OF ILLINOIS.

CUPOLA-CHARGING DOOR.

Application filed April 14, 1923. Serial No. 632,047.

To all whom it may concern:

Be it known that I, BRADFORD H. WHITING, a citizen of the United States, residing at Chicago, in the county of Cook and State 5 of Illinois, have invented a certain new and useful Improvement in Cupola-Charging Doors, of which the following is a specification.

This invention relates to cupola furnaces 10 for melting metals of various sorts. The object of the invention is to provide a door for the metal intake opening of such a character that the operator outside the cupola can view the interior thereof in comparative 15 comfort, notwithstanding the intense heat of the cupola; can insert a poker or the like for stirring up the contents of the cupola and through which material for combustion in the furnace may be inserted with the 20 minimum outward passage of heat from the interior of the cupola. The further object is to provide a convenient mounting for the door by which it may be moved to different 25 positions as the work in and about the cupola may require.

The invention consists in means capable 30 of attaining the foregoing and other objects; which can be easily and cheaply made; which is satisfactory in use and is not readily liable to get out of order.

More particularly, the invention consists 35 in numerous features and details of construction which will be hereafter more fully set forth in the specification and claims.

Referring to the drawings in which like 40 numerals designate the same parts throughout the several views—

Figure 1 is a fragmentary side elevation 45 of a cupola furnace equipped with mechanism of this invention in its preferred form, showing a conventional form of device for passing the contents of a charging car into the cupola.

Figure 2 is a plan view on the line 2—2 of 50 Figure 1.

Figure 3 is a side elevation taken from 55 the left of Figure 1 showing the door mechanism of this invention.

Figure 4 is a central, sectional detail view 60 through the cupola and door of this invention, taken on the line 4—4 of Figure 3.

Figure 5 is a plan detail view on the irregular line 5—5 of Figure 3.

The improved door is shown applied to a 65 conventional form of cylindrical cupola 10

having the usual intake port 12 with an inclined bottom edge 14 over which material delivered in any suitable manner, as for instance, from a car 16 is adapted to be passed. In Figure 1, the wheels 18 of the car are 60 shown mounted upon a conventional form of tilting mechanism 20—22 adapted to move the car from the position shown to an inclined position where the contents of the car will slide over port opening 14 into the 65 cupola. The complete operative mechanism for so tilting the car is shown, for instance, in Patent No. 911,725 to J. Hyslop, dated February 9, 1909.

Any cupola or furnace which thus handles 70 material in car load lots necessarily requires in the cupola an intense heat and the problem to be solved by this invention is to provide a practical closure for the port 12 through which an operator stationed adjacent to this port can view the contents, and 75 through which at least small quantities of outside material may be passed into the furnace without completely opening the large 80 port 12 and thus allowing the heat in the furnace to flare out into the furnace room. The desired result is accomplished by placing on opposite vertical sides of the port 12 trackways or guides 24 for a vertically reciprocable cross-head 26 carrying a multiplicity 85 of parallel depending chains 28 forming in the position of Figures 1, 3 and 4, a curtain completely covering the port 12. This cross-head 26 is vertically reciprocable in the track device 24 by any suitable 90 means; as, for instance, a piston rod 30 entering and operatively controlled by an air cylinder 32 attached as at 34 to the exterior walls of the cupola. Conventional 95 means, not shown, is provided for admitting compressed air or other motive fluid to this cylinder below the piston 36 on rod 30 to in conventional manner elevate the piston and consequently the cross-head 26 and the suspended curtain of chains 28. In the 100 construction shown in the drawings, it is assumed that the weight of the cross-head and curtain of chains will always carry the curtain down to the position shown in the drawings when the motive fluid is allowed 105 to escape from below piston 36 in cylinder 32, but motive fluid may also be conveniently applied to the upper end of cylinder 30 above piston 36 to move the cross-head downward should occasion ever require it.

2
The chains 28 are made of sufficient size and of such a heat resisting material that they do not readily burn up under the heat produced by the normal operation of the cupola. They are placed sufficiently close together so that they form in fact under normal conditions a practically solid metal curtain except for the interstices which are necessarily present at the junctures of the 10 various chain lengths. In actual practice, these small openings through the curtain are of sufficient size so that the operator can view the interior of the cupola without any objectionable amount of heat passing 15 through the curtain to the furnace room. When it becomes necessary for the operator to stir up the contents of the cupola, he can insert a poker or the like through the curtain at any desired point, the adjacent chain 20 swinging aside as may be required for this purpose, and yet in this case, the opening through the curtain will be so comparatively small that no objectionable amount of heat will escape through the curtain. When a 25 carload of material is to be charged in the cupola, the curtain may be left in the position shown and the passage of the material down the inclined surface 14 be relied upon to simply swing the curtain inward to the 30 right as viewed in Figure 4, sufficiently to

allow the material to pass, or the operator can manipulate cylinder 32 to elevate the cross-head 26 and consequently the entire curtain to such a height that the chains 28 of the curtain entirely clear the port 12. 35

The mechanism of this invention has been incorporated in a commercial structure which actually produces the desired satisfactory results heretofore enumerated.

Having thus described my invention, what 40 I claim as new and desire to secure by Letters Patent is:

The combination with a cupola having a side port with the lower defining wall of which is inclined downwardly towards the interior 45 of the cupola; of a curtain for closing said port composed of a multiplicity of closely placed, loosely hanging chains suspended from their tops only and contacting at their free lower ends with said inclined lower defining wall of said port, whereby said port is closed normally by said curtain and whereby fuel deposited on said inclined wall 50 will flow under said curtain without the necessity of manually manipulating the 55 latter.

In witness whereof, I have hereunto subscribed my name.

BRADFORD H. WHITING.
